UNITED STATES PATENT OFFICE.

GUIDO M. SACERDOTE, OF NEW YORK, N. Y.

MANIFOLDING TYPEWRITER.

Application filed June 23, 1923. Serial No. 647,275.

This invention relates to manifolding typewriters, and its primary object is to provide a device of novel and improved design, adapted to be mounted on a typewriter, or embodied in its construction, whereby a plurality of copies may be produced using rolls of paper as a source of supply.

Another object is to provide a device of the class mentioned, which includes certain novel improvements whereby ease of operation and satisfactory results are assured.

A further object is to provide, in a device of the class mentioned, a novel and improved arrangement of manifolding ribbons, permitting operation of the typewriter in the usual manner.

With these and other objects in view, as will more fully appear as the description proceeds, this invention furthermore consists in certain novel and improved constructions and arrangements of parts, as will be hereafter fully described and claimed in the appended claims.

Referring to the drawings:

Fig. 1 is a side view in elevation, partly broken away, of a device embodying my invention in the form of an attachment mounted on a standard typewriter;

Fig. 2 is a fragmentary front view in elevation, partly sectioned, of the same;

Fig. 3 is a plan view of the same, partly broken away;

Fig. 4 is a detail side view in elevation showing a different style of paper detaching device;

Fig. 5 is a detail fragmentary view in perspective showing the arrangement for producing copies; and,

Fig. 6 is a detail fragmentary view in perspective of an arrangement which may be adopted to insure proper matching of blanks, and to prevent slipping.

In said drawings, Figs. 1, 2, 3, represent a device embodying my invention, in the form of an attachment adapted to be directly mounted on the carriage of an ordinary typewriter, and designed for the production of one original and two copies.

The same comprises a frame composed of a right side 10 and a left side 11, connected rigidly together by means of tie rods 12, 13, 14, 15, and mounted on the typewriter carriage 16, being secured thereto by means of screws 17, 18, or in any other suitable manner. The drawings represent a type of

standard typewriter among those found on the market, and specially machined screws 17, 18, have merely been substituted for other screws already provided at the same places, retaining the carriage release levers 19, 20, so as to make it easy to mount the attachment on existing machines.

The rear lower part of the frame side pieces is also shown inserted over the column spacing bar 21, and connected thereto, and to the supporting brackets therefor 22, 23, by means of screws 24, 25; so that the mounting of said frame on the carriage is firm and effective.

From this it follows that the frame, and all its parts, travel with the carriage of the typewriter, which is operated in the usual manner, and which of course carries, among other parts, the platen 26, and the space indicating bar 27. The platen is supported by a frame, of which 28, 29, designate the end pieces, which may be raised from the position shown in the drawings, where small, or lower case type is printed, to the upper position where higher case or capital letters will be printed, in a manner which is well known, by means of shift keys provided for this purpose.

The frame constituted by side pieces 10, 11, and by tie rods 12, 13, 14, 15, is designed to support the rolls of paper which have to be fed to the platen; in the present instance the rolls being three, one, 30, supplying paper for the originals, and two, 31, 32, supplying paper for first and second copies. These rolls are respectively mounted on shafts 33, 34, 35, inserted in open bearings 36, 37, 38, provided in each side piece, and said shafts are provided, if necessary, with suitable positioning means for the rolls, for instance collars 39, secured on the shafts by set screws 40.

The ends of the strips of paper 30', 31', 32', issuing from the rolls, are fed to the platen in the usual manner, as shown in Fig. 1, and at the front or writing side, copying ribbons 41, 42, are respectively inserted between strips 30', 31', and 31', 32', as clearly shown in Fig. 5; the device is then in position to simultaneously produce both original and copies, simply by operating the typewriter in the usual manner.

Ribbons 41, 42 (see Fig. 5), stretch for the entire width of the paper, and preferably, in order to utilize the full capacity of the

platens, from one end of the platen to the other; and in order to insure their satisfactory operation, the same must be gradually fed in a longitudinal direction, and the 5 tendency of the paper, when fed for line spacing purposes, to carry the ribbons out of proper alignment, must be overcome.

In addition to this, means must be provided for reversing the direction of the longitudinal feed of the ribbons, when entirely rewound on the feeding reel, in a manner similar to that adopted in typewriters in connection with the ribbons with which same are ordinarily supplied. To further enhance the usefulness of the device illustrated, however, I prefer to provide means whereby the reversal of the ribbon feed will take place automatically, as will appear at a later stage of this description.

20 For simplicity of design, all the copying ribbons are wound on the same reels, one at each end, designated by numerals 43, 44, and are guided in their course of travel, by rollers 45, 46, 47, 48, and by slots or passages 49, 50, formed between the front edge of platen frame end pieces 28, 29, and bridge pieces 51, 52, for this purpose attached thereto in any suitable manner for instance, by means of screws or rivets as shown in Fig. 1.

30 The ribbon 53, with which the typewriter is already provided, is left untouched, and is used to produce the originals in the ordinary manner.

In Fig. 2, the copying ribbon feeding mechanism appears in the position where the reel at the left, 44, is pulling the ribbons, causing the same to unwind from the reel at the right, 43; the supply at this end however, being close to exhaustion, and the feed reversal mechanism being about to be operated.

From the arrangement shown in the drawings, where lower guiding rolls 46, 48, appear mounted well at the front, on a plane 45 with the axis of the platen, or close thereto, it is seen that the shifting of the platen from the lower to the upper case, will not be hampered in the slightest degree; the strands of copying ribbons alongside the platen following, of course, in its motion. This is a detail of considerable importance, inasmuch as it permits shifting of the platen even though the ribbon spools are mounted on the main frame, and remain stationary in relation to 55 the platen frame.

As stated above, the feeding of the paper for line spacing purposes, will cause the same to tend, by friction, to carry the copying ribbons upward, out of alignment with 60 the striking position of the types. It is obvious that this action may be counterbalanced by maintaining the ribbons under tension, by means of springs or otherwise; but I attain the same end without the use of 65 any additional parts, simply by providing

means whereby the feeding of the ribbons will take place after the paper has been fed for line spacing purposes, so that even if the ribbons had been carried out of alignment through the feeding of the paper, the tension which the feeding reel will subsequently exert on the ribbons, will again stretch the same.

Reels 43, 44, which are of the type ordinarily used on typewriters, are respectively 75 mounted on shafts 54, 55, and are secured in position by means of screws 56, 57; said shafts are in their turn loosely mounted on bearings 58, 59, carried by brackets 60, 61, attached to side pieces 10, 11.

Said shafts 54, 55, are rotated by means of sprocket wheels 62, 63, mounted on the same, and respectively connected by chains 64, 65, to sprocket wheels 66, 67, loosely mounted on a shaft 68, which is carried by a bracket 69 80 attached to space indicating bar 27.

Sprocket wheels 66, 67, are each provided with a clutch member 70, 71, which may be caused to interlock with movable clutch members 72, 73, keyed on shaft 68; said 90 clutch members 72, 73 being respectively integral with collars 74, 75, mounted on a common shifting rod 76 which is also carried by bracket 69. Clutch members 72, 73, are so arranged that when one is engaged to drive 95 its respective sprocket wheel, the other one is disengaged, and vice versa. In the drawing it appears that clutch member 73 is in driving engagement with sprocket wheel 67, while clutch member 72 is disengaged; therefore shaft 55 will be driven, causing reel 44 to pull the copying ribbons, unwinding the same from reel 43.

However, if rod 76 is shifted to the left, clutch member 73 will become disengaged, 100 and clutch member 72 will enter into driving engagement with sprocket wheel 66; and if shaft 68 is now caused to rotate in the same direction as previously, reel 43 will now pull the copying ribbons in the reverse direction, causing the same to unwind from reel 44, shaft 55 of which is free to revolve.

Any suitable type of hand operated means may be used to shift rod 76 when necessary; but I prefer to cause its automatic operation 115 as follows:

Each frame side piece, 10, 11, carries a bracket 77, 78, on which is pivotally mounted at 79, 80, a lever 81, 82. These two levers are respectively formed with a side extending arm 83, 84, provided with slots 85, 86, through which the copying ribbons are inserted; said slots being wide enough to accommodate the thickness of the ribbons, but no more.

Said levers 81, 82, also are formed with forked arms 87, 88, engaging collars 74, 75, respectively. The ribbons are provided near each inner end, with a clip 89 secured thereto, and increasing their thickness, so that, as 130

seen in Fig. 2, as the feeding reel continues to pull the ribbons, clip 89 will gradually force arm 83 of lever 81 downward, causing arm 87 to shift rod 76 toward the left. 5 Thus sprocket wheel 67 will become disengaged from clutch member 73, and reel 44 will cease pulling the ribbons.

Each arm 87, 88, is attached to its respective bracket 77, 78, by means of a tension spring 90, 91, fixed to a point 92, 93, in line respectively with pivots 79, 80 and with the central line of arms 87, 88, when midway between their two extreme positions. In other words, if rod 76 is in the 15 position shown in the drawings, where the forked ends of arms 87, 88, are to the right of their respective pivots, springs 90, 91, tend to maintain said arms in said position.

However, if clip 89 pushes down arm 83 to 20 a point where the forked ends of arms 87, 88, will have passed their intermediate position, and will assume a position slightly to the left of pivots 79, 80, springs 90, 91, which have in the meantime been stretched, will 25 cause said arms to snap towards their extreme left position as soon as the dead point has been passed. It is therefore sufficient to assemble the different parts in such a manner that clutch member 73 will become 30 entirely disengaged after the dead point of arms 87, 88, has been passed, to insure continued operation of shifting rod 76 to completion; and the same remark applies to clutch member 72 when the shifting rod 35 is moved in the opposite direction.

As soon as clutch member 72 has become 40 engaged to sprocket wheel 66, 43 will become the driven reel, and the ribbons will move in the reverse direction; levers 81, 82, however, retaining the newly acquired positions shown in dotted lines in Fig. 2, up to 45 the time when the clip at the left end will force down arm 84, again shifting rod 76 towards the right.

The feeding of ribbons 41, 42, only takes 50 place intermittently, and the actuating means thereof are arranged so that the ribbons will be fed during the return motion of the carriage, after the line spacing feeding of the paper has occurred. This is obtained merely by using the line spacing lever 94, with which the typewriter is provided, in the usual manner, the action of the same being first to operate the platen so as to 55 feed the paper, and then to pull the carriage towards the right, in order to start a new line. The actuating means for the ribbon feed become operative during said return travel of the carriage, and are inoperative 60 during its step by step travel caused by the writing, in the reverse direction.

Said actuating means comprise a rack 95 secured to the top of the typewriter frame by means of screws 96; a gear 97 loosely 65 mounted on a shaft 98, rotatable within a

bearing 99 integral with bracket 69; said gear being in mesh with said rack; a worm 100 mounted on said shaft in mesh with a worm wheel 101 mounted on shaft 68; and a ratchet wheel 102 operated during the 70 return stroke of the carriage by a pawl 103 mounted on a disc 104 integral with gear 97, fixed on shaft 98. When the carriage moves towards the left, gear 97 is caused to revolve also towards the left, 75 sprocket wheel 102 remaining stationary. When lever 94 is operated, the platen is first caused to revolve for a given angle, and then the carriage is pulled to the right. The sense of the rotation of gear 97 becomes then reversed, and pawl 103 carried thereby will engage ratchet wheel 102 causing shaft 98 to rotate, and causing therefore, 80 through worm 100 and worm wheel 101, the rotation of shaft 68 and of the reel 85 connected thereto.

It is obvious that a positive ribbon feed, such as described, is preferable to a step-by-step motion such as might be caused by utilizing the same detent mechanism which 90 is used for feeding the original printing ribbon in most typewriting machines. Such a step-by-step feed might interfere with the step-by-step feed already obtained owing to the intermittent motion of the platen caused 95 by the operation of the type-bars, and would make it necessary to employ special timing devices in order to insure proper feed of the ribbon. The main objection to such a method of feeding the manifolding ribbon or 100 ribbons, however, resides in the fact that it is absolutely essential, in a machine of this kind, to preserve sensitive response of the carriage to the pulling action of the spring, each time a key is operated. It is upon this 105 sensitive response that the speed attainable with a machine depends.

In an ordinary typewriter the ribbon feed does not seriously interfere with the carriage feed, although both feeds are produced at the 110 same time by the action of the same spring; but in a manifolding typewriter, the manifolding ribbon or ribbons are inserted between adjoining sheets, and are subjected to considerable friction for the entire width of the sheets. It takes quite a positive pull on the ribbon, in order to feed it under these conditions, and an even tension exerted by such a spring as available would be decidedly unreliable in overcoming this friction. 115 To do this, the tension of the spring would have to be increased beyond the limits which can be safely used.

It is of course possible to use a separate 120 spring for this purpose; but even then, the friction to be overcome is not always the same, and at times a jerk or a sudden action is really necessary in order to pull the ribbon through. Therefore I prefer to positively drive the ribbon feeding means, pref- 125

erably at the time when, or after the paper feed, or line spacing has occurred.

As a consequence, the manifolding ribbon feed operates only at relatively long intervals, as is the case, for instance, if the feed is operative only during the return movement of the carriage. In these conditions, while it is not strictly necessary to feed the manifolding ribbon for the entire length of the line previously written, it is however necessary to feed a good length of ribbon each time.

A feed corresponding to one step of the ordinary feed would not do, since in practice this would correspond to a total feeding of a length of ribbon approximately equal to one-half the width of an ordinary page, while the entire page is being written. A ribbon would wear out very quickly under these conditions, since it is well known that a ribbon will work much better, and will last a much longer time, if it is allowed to become "restored" frequently while in use.

This "restoration" is useful both in order to rest the fibers of the ribbon, which would quickly become stretched and worn under frequent hammering of the type bars, and in order to give a chance to that portion of the ribbon which has been printing a character or a line, to recover part of the ink which it has thus lost, through contact with other portions of the ribbon wound upon the same spool. At the rate stated, each point of the ribbon would have to print possibly sixty to eighty letters before actually reaching the rewinding spool, and its usefulness would be destroyed long before through sheer fatigue and lack of a sufficient ink supply.

For this reason alone, therefore, it is necessary to provide a relatively long feed of the manifolding ribbons, when such feed takes place. But it is also necessary to do this for another reason, which has been mentioned before. When the platen is rotated for line spacing purposes, the friction between the paper layers and the interposed ribbons tends to drag the ribbons out of proper alignment.

The same happens, to a more pronounced degree, when the platen is rotated in the reverse direction. Therefore the manifolding ribbon or ribbons should be restored to a position of proper alignment, or maintained in such position, at the time when, or preferably after, such movements of the platen take place. In practice it is difficult to prevent such a dragging of the ribbons out of alignment; therefore provisions should be made for their restoration to proper position for printing, if serious curtailment of the usefulness of the device is to be avoided.

Now it is not possible, in practice, to restore the ribbons to their proper alignment, unless a substantial longitudinal movement

of the ribbon is effected; this movement may vary anyway from about one-half inch to the length of an entire line, but it would be very dangerous to rely on a smaller movement, as the device might fail to accomplish its purpose at all times.

This necessity makes it advisable to insure a condition where the movement of the platen for line spacing purposes has been terminated when the ribbon feed is effected, and this can be obtained by means of the line spacing lever, as previously pointed out. In addition, the necessity of a long feed makes it imperative to provide an instantaneous reversal of the ribbon feed, because the rapid and positive motion of the carriage, and its momentum, might cause the ribbon to break if a sudden resistance is encountered in its operation.

The paper of which the rolls are composed, may consist of strips perforated at intervals, so that the filled slips may be detached by tearing the perforations. For letter writing, however, it is preferable to produce sheets with neat sharply cut edges, and to this end suitable cutting devices may be provided. As an illustration, a type of shearing device is illustrated in the drawings, for the accommodation of which slots 105, 106, have been provided at each side of the frame. Said slots are elongated to permit adjustment of the cutting or shearing device, to conform with the heading of the next sheet or blank, the printed matter of which may be used as a gauge.

Said shearing device consists of a stationary plate 107 carrying a stationary knife 108, and provided with an apron 109, secured in position by means of bolts 110, 111, inserted through slots 105; and a movable plate 112, pivotally mounted at 113 on to plate 107, said plate 112 carrying the other knife 114, and being normally maintained in its detached position shown in Fig. 1 by the action of a tension spring 115 attached to an arm 116 integral with said plate.

In this position, the paper in use will be gradually fed through the space between the edge of knife 114 and knife 108, coming out at 115. Plate 112 also carries a pressure plate 116', which is slidable crosswise, being mounted on pins 117, but is maintained in its outward position by the action of springs 118 pressing against the heads of said pins.

When plate 112 is operated by means of a clip 119 integral therewith and projecting through slot 106, to cut the paper, said paper will be pressed between apron 109 and pressure plate 116', and slipping of the same will be prevented, and an even cut insured. As soon as clip 119 is released, spring 115 will cause plate 112 to return to its normal position, and the writing on the next sheet may be started.

The requirements for certain forms of documents, like shipping slips, order records, etc., are not very exacting in what concerns the appearance of their edges, and in such cases tearing up devices of a suitable design 5 may be used instead.

A device of this character is illustrated in Fig. 4, shown applied in connection with slots 105', 106', similar to slots 105, 106. Said 10 device consists of a stationary plate 120, secured in position by means of bolts 110', 111', carrying a plate 121 formed with a pressure edge 122, pivotally mounted at 123. Said plate 121 is integral with arms 124, 15 to which a tension spring 125 is attached tending to hold edge 122 of plate 121 pressed against plate 120, as shown at 121' in dotted lines. Plate 120, however, carries a stop member 125' pivoted at 126, and formed with an indentation 127 adapted to interlock with 20 edge 122, normally holding the same in a position detached from plate 120. A tension spring 128 tends to pull stop member 125' downwardly, and said stop member is provided with a handle 129 projecting through 25 slot 105', by means of which the same may be operated.

In a similar manner, arms 124 are provided with a handle 130 by means of which 30 the same may be operated.

The device is normally set in the position shown in the drawing, where the paper strips are free to move between plate 120 and edge 122. When the filled blanks have to be 35 detached, stop member 125' is raised by means of handle 129, freeing edge 122, and spring 125 will then cause said edge to press the paper against the surface of plate 120. The slips may then be detached by a well 40 known method, by tearing the same along the holding edge 122.

By means of handle 130, plate 121 is then moved back, until through the action of spring 128, stop member 125' is again free 45 to snap into engagement with edge 122, again holding plate 121 in its normal position. The operation on the next sheets may then be started.

In the feeding of paper by means of the 50 platen, a slipping tendency is liable to develop, especially when a number of copies are produced, which may cause the various sheets or strips to be fed of uneven quantities; in other words, a relative motion taking place between the various sheets or strips. This is not open to serious objections when the rolls consist of blank paper, or of 55 printed paper for the original only, and blank paper for the copies; but when a number of 60 copies of printed and sometimes numbered blanks have to be produced, it is essential that corresponding copies of the same register at all times, and means to prevent slipping should preferably be provided, if frequent 65 readjustments are to be avoided.

This result may be achieved in any suitable manner, and one among the arrangements which may be adopted is illustrated in Fig. 6. In the same, the strips of paper are provided with equidistant perforations 70 at the sides, at 131, adapted to be engaged by teeth 132 of a cylinder or roll 133, adherence of the strips on to said roll being insured by another roll 134 provided with grooves 135 to accommodate said teeth. Said rolls 75 133, 134, are preferably mounted on the device between the rolls of paper and the platen 136, and the simultaneous engagement of the perforations of corresponding blanks by teeth 132 will insure their correct matching 80 in a simple and positive manner.

In the form illustrated, the device is unobtrusive and practical, inasmuch as the line of vision of the operator is not interfered with, and the operation of the typewriter 85 remains unchanged. Experience has proved that the carriage of the average machine can stand considerable weight and still readily respond to the action of the keys; but of course, when a large number of rolls of 90 paper should be used, or rolls of extra large diameter and weight, it may be preferable to mount the frame supporting the same on a separate stand back of the typewriter, and to provide suitable means for causing the 95 same to follow the movements of the typewriter carriage.

It is obvious, that when some of the matter written on the original should have to be left off some of the copies, the strips used 100 may accordingly be of different width, or set off at one side of the necessary quantity.

The re-rolling of some of the strips without cutting is also possible, and this may represent a desirable feature when it should 105 be an advantage to keep records in a chronological or numerical order.

It is obvious from all that precedes, that devices embodying my invention may be produced in various styles and forms, according to the purposes for which the same are intended, and may either be in the form of attachments for existing machines, or may form integral part of especially designed machines.

I therefore reserve myself the right to carry my invention into practice in all those ways and forms which may enter, fairly, into the scope of the appended claims.

I claim:

1. In a typewriting machine, the combination with a carriage, of a platen shiftable to lower and upper case printing positions mounted on said carriage, a ribbon extending along the printing line of said platen, a platen carrier comprising two end frames, each provided with a slot guiding said ribbon and deflecting it towards the front of the machine, spools mounted on said carriage one at each end thereof rotating on 115 120 125 130

substantially vertical planes, and additional guiding means for said ribbon mounted one at each end of said carriage at a distance from said platen, said additional guiding means being located on a plane substantially at right angle to the shifting movement of said platen, passing through or close to the space delimited by the extreme positions of said printing line due to said shifting movement.

2. In a typewriting machine, the combination with a carriage, of a frame mounted on said carriage, a platen shiftable to lower and upper case printing positions also mounted on said carriage, a ribbon having a portion extending along the printing line on said platen from end to end thereof, a carrier for said platen, comprising two end frames each provided with a slot guiding said ribbon and deflecting it towards the front of the machine, spools for said ribbon mounted one at each side of said frame rotatable on substantially vertical planes, and additional guiding means on said frame directing said ribbon from said spools to said slots, said additional guiding means being located at a distance from said platen on a plane substantially at right angle to the shifting movement of said platen, passing through or close to the space delimited by the extreme positions of said printing line due to said shifting movement.

3. In a typewriting machine, the combination with a carriage, of a frame mounted on said carriage, a platen shiftable to lower and upper case printing positions also mounted on said carriage, a ribbon having a portion extending along the printing line of said platen from end to end thereof, a carrier for said platen comprising two end frames each provided with a slot guiding said ribbon and deflecting it towards the front of the machine, winding spools for said ribbon mounted one at each end of said frame rotatable on planes at right angle to the direction of carriage travel, guiding means for said ribbon located at a distance from said platen at a plane substantially at right angle to the shifting movement of said platen, passing through or close to the space delimited by the extreme positions of said printing line due to the shifting movement of said platen, said guiding means directing said ribbon from said spools to said slots, a shaft actuated by the return movement of said carriage, adapted to drive either one of said spools, causing feed of said ribbon from end to end thereof, and quick automatic means controlled by said ribbon effecting a reversal of the said ribbon feed.

4. In a typewriting machine, the combination with a carriage, of a stationary frame and a platen shiftable to lower and upper case printing positions mounted on said

carriage, a ribbon having a portion extending along the printing line on said platen from end to end thereof, means shiftable with said platen maintaining said ribbon in printing position, two spools for said ribbon rotatably mounted on said frame, guiding means for said ribbon, on said frame, allowing the shifting movement of said platen and ribbon to occur, without substantially affecting the tension conditions of said ribbon, a shaft mounted on said carriage, adapted to drive one or the other of the said spools, means controlled by the return movement of said carriage operating said shaft, quick-acting automatic means, controlled by said ribbon, governing the driving connections between said shaft and said spools, means for mounting rolls of paper on said frame, a guide plate mounted on said frame, above said platen, upwardly inclined in a direction substantially tangential to the front part of said platen, and paper cutting means associated with said guide plate, and normally spaced therefrom, adjustable to and from said platen.

5. In a typewriting machine, the combination with a carriage, of a frame and a platen mounted on said carriage, and a paper severing device mounted on said frame, said device comprising a transversely extending blade member traveling with said frame, said blade member being tiltable about a longitudinally directed horizontal pivot, and being adjustable to and from the platen along an upward direction substantially tangential to the front part of said platen.

6. In a typewriting machine, the combination with a carriage, of a frame and a platen mounted on said carriage, a plate mounted on said frame above said platen, upwardly inclined in a direction substantially tangential to the front part of said platen, and a blade member tiltable about a longitudinally directed horizontal pivot cooperating with said plate, said blade member and plate extending transversely of and traveling with said frame.

7. In a typewriting machine, the combination with a carriage, of a frame and a platen mounted on said carriage, a plate mounted on said frame above said platen, upwardly inclined in a direction substantially tangential to the front part of said platen, and adjustable to and from said platen in the same direction, and a blade member tiltable about a longitudinally directed horizontal pivot, carried by and cooperating with said plate, said blade member and plate extending transversely of and traveling with said frame.

8. In a typewriting machine, the combination with a carriage, of a frame and a platen mounted on said carriage, a plate mounted on said frame above said platen, upwardly

inclined in a direction substantially tangential to the front part of said platen, and adjustable to and from said platen in the same direction, a blade member tilttable about a longitudinally directed horizontal pivot, carried by and cooperating with said plate, and means for normally holding said

blade member at a distance from said plate to allow feeding of the paper between said plate and blade member, said blade member and plate extending transversely of and traveling with said frame.

GUIDO M. SACERDOTE.
